CLAIM

The ornamental design for an adjustable wall rack for holding hair treating devices, substantially as shown and described.

DESCRIPTION

FIG. 1 is a perspective view of the adjustable wall rack for holding hair treating devices showing our new design;

FIG. 2 is a side elevational view taken from the left of FIG. 1, the adjustable slide being in its lowest position;

FIG. 3 is a front elevational view of FIG. 2;

FIG. 4 is a rear elevational view of FIG. 2;

FIG. 5 is a top plan view of FIG. 2;

FIG. 6 is a bottom plan view of FIG. 2; and

FIG. 7 is an inverted perspective view of the design of FIG. 1 showing an alternate position.
